DART GAME BOARD

James W. Sowerbrower, Alexandria, Va.
(3713 Nile Road, Davidsonville, Md. 21035)

Filed Mar. 7, 1973, Ser. No. 338,937

Term of patent 14 years

Int. Cl. D21—01

U.S. Cl. D34—5 SS

The figure is a front elevational view of a dart game board showing my new design.

The game board is of conventional thickness for dart boards.

I claim:

The ornamental design for a dart game board, as shown and described.
